UNITED STATES PATENT OFFICE.

JAMES TRIPP, OF NEW YORK, N. Y., ASSIGNOR TO CHARLES T. BECKWITH
AND ELLEN F. BECKWITH, BOTH OF OBERLIN, OHIO.

SEWING-MACHINE SHUTTLE.

SPECIFICATION forming part of Letters Patent No. 276,731, dated May 1, 1883.

Application filed August 3, 1882. (Model.)

To all whom it may concern:

Be it known that I, JAMES TRIPP, a citizen of the United States, residing at New York city, in the county and State of New York, have invented certain new and useful Improvements in Shuttles for Sewing-Machines, of which the following is a specification.

My invention relates to improvements in the tension-springs of sewing-machine shuttles, and in a pivoted heel-plate employed in conjunction therewith for holding the bobbin in position.

The nature of my invention will be thoroughly explained by means of the accompanying specification and the drawings annexed thereto, which form part of the same.

Referring to the drawings, Figure 1 is a plan; Fig. 2, a front view; Fig. 3, a rear view; Fig. 4, a side view; and Fig. 5, a sectional view of Fig. 4, showing the parts of my improved shuttle in position for use. Fig. 6 is a plan view of my improved shuttle with the bobbin removed and the retaining parts in an open condition. Fig. 7 is a plan view of the same, 25 with the bobbin inserted and the heel-piece in place over the end thereof, ready to be latched by the combined tension-spring and heel-plate holder. Fig. 8 is an end view, showing the parts in the same position as represented in Fig. 6. Fig. 9 is a plan view, showing the bobbin separately. Fig. 10 is a side view, Fig. 11 a section, Fig. 12 a plan, and Fig. 13 an end view, of the heel-plate separate. Fig. 14 is a plan view, Fig. 15 an under side view, Fig. 16 30 a front view, and Fig. 17 a section, of the combined spring heel-plate holder and threader separately.

In each of the views similar letters of reference are employed to indicate corresponding parts wherever they occur.

A represents the main body or shell of the shuttle, which on its side *a*, facing the shuttle-race, is curved, and at *a*¹ is provided with a nose in which is formed a recess, *a*², for the reception of a holding-point affixed to the cradle or holder in which the shuttle rests. The shuttle A is formed with the usual internal recess, *a*³, for the reception of the bobbin B. In the forward portion of this recess *a*³ is formed a bearing, *a*⁴, for the reception of one end, *b*, of the spindle of the bobbin B, the opposite end, *b*¹,

of which is held by a heel-plate, C, which is formed on the end of an arm, *c*, pivoted to the upper side of the shuttle-shell A. In the center of the heel-plate C is a hole which forms a bearing for the opposite end, *b*¹, of the bobbin. The recess *a*³ in the shell A is cylindrical, and the heel-plate C is so formed as to fit snugly into its mouth *a*⁵, except where the heel-plate is cut away, so as to form an elongated notch, *C*', for the reception of the locking portion of the tension-spring E, as hereinafter explained. A small notch, *A*², is formed in the upper part of the shell A, at the mouth *a*⁵ of the recess *a*³, for the purpose of accommodating the bent portion of the arm *c* of the heel-plate C, and thereby assist in holding the heel-plate C in proper position.

D is a slot formed in the upper side of the shuttle for the passage of the thread to the eye or hole *d* when threading the shuttle.

Supposing the parts to be in the position shown by Figs. 6, 7, and 8, and it is desired to insert the bobbin B, the bobbin B is pushed into the recess *a*³, so that one end, *b*, of its spindle shall enter the bearing *a*⁴. The heel-plate C is then turned round from the position shown by Figs. 6 and 7 into such position that it can be thrust backward over the opposite end *b*¹ of the spindle of the bobbin, so that it shall assume the position indicated in Figs. 1 and 5, the lateral motion of the heel-plate being provided for by means of a small slot, *c*', which is formed in the end of the arm *c*, and through which passes a retaining-pin, *c*², affixed on the upper side of the shuttle-body A.

E is the tension-spring, which is pivoted in a recess, *a*⁵, in the top of the shell A, and is there retained by a binding-screw, *e*. This tension-spring E is provided with a suitable threading-slot, *e*', and at *e*² is bent vertically and then returned at *e*³, so as to form a locking-piece for the heel-piece C, while at the same time the heel-piece C forms a retaining means for the tension-spring E. After the heel-piece C has been turned and pushed back into position, (shown by Fig. 8,) so as to hold the end *b*¹ of the spindle of the bobbin B, the tension-spring E is turned on its binding-screw *e* from the position shown by Figs. 6, 7, and 8, so that its vertically-bent portion *e*² shall come at the rear of the heel-piece C, so

as to lock the heel-piece in position, while at the same time its returned portion e^3 enters the notch C' under the heel-piece and secures itself firmly in position. The returned portion also serves, by coming against the end of the axis of the bobbin B , to steady the same in position.

A^2 is a notch formed in the lower front side of the shelf A , for the purpose of allowing of the free passage of the returned portion of the spring E when it is being turned for the purpose of locking or unlocking the heel-piece C .

After the thread has been passed through the hole d it is threaded into the eye E' by means of the threading-slot e' , and is drawn off in the ordinary manner for use, the amount of tension imparted to the thread being regulated by means of the screw e .

By my peculiar construction of the pivoted tension-spring and the pivoted heel-piece great facility is obtained for the insertion and removal of the bobbin from the shuttle by reason of the parts being capable of removal sideways by the simple pressure of the fingers without necessitating the raising of a spring to release a catch or other means from a notch or hole, as is the usual manner, and which either necessitates the employment of a tool or instrument or the risk of breaking the nails of the lady or other person employing the device, which is a fact of daily occurrence and experience with persons using sewing-machines with shuttles of the ordinary and general construction.

Another advantage of my improvement is that the holding parts of the tension-spring go entirely over and under the heel-piece, thereby giving greater firmness and rigidity thereto.

Although I have shown my improvements applied to a shuttle adapted for use in a machine having a circular race, the same may readily be applied to shuttles for use in machines constructed with straight races.

Having thus described my invention, what I claim, and desire to secure by Letters Patent, is—

1. A sewing-machine shuttle having a removable bobbin, and a removable heel-piece formed on the end of a slotted bar pivoted to the upper side of the shuttle-shell, a pivoted tension-spring formed with a vertically bent and returned portion passing entirely over and under the heel-piece, the returned portion be-

ing so formed as to pass between the under side of the heel-piece and the shell and latch 55 and hold the pivoted heel-piece and bar and the pivoted tension-spring in position, substantially as and for the purpose described.

2. In a sewing-machine shuttle, a removable heel-piece constructed with a central opening 60 adapted to act as a bearing for one end of the bobbin, and having a slotted arm pivoted and sliding on a pin and secured thereby to the side of the shuttle, near to its heel, so as to admit of the bearing of the tension-spring E on 65 the shell or body of the shuttle, between said pin and the binding-screw e , so as to secure the necessary tension of the thread, substantially as and for the purpose specified.

3. In a sewing-machine shuttle, a removable 70 heel-piece formed on the end of a slotted bar pivoted to the upper side of the shuttle-shell, and having a notch on its under side constructed so as to admit of the passage of the returned portion of the tension-spring beneath the same, 75 and the locking of heel-piece and the tension-spring in position, substantially as shown and described.

4. A sewing-machine-shuttle shell having 80 on the side of its heel a notch adapted to admit of the passage of the locking end of a pivoted tension-spring, which passes entirely over and under a heel-piece, holding the same in position, substantially as and for the purpose specified.

5. In a sewing-machine shuttle, the combination, with a shell, A , and bobbin B , of the heel-piece C , connected to the shell A by a slotted arm, e , pivoted and sliding on a pin, c^2 , and secured in position by a tension-spring, E , 90 substantially as set forth.

6. In a sewing-machine shuttle, the combination, with a shell, A , formed with a notch, A^2 , and a bobbin, B , of the heel-piece C , formed with a notch, C' , and connected to the shell A 95 by a slotted and pivoted arm, e , and pivoted tension-spring, E , having a self-retaining and heel-plate-holding portion, e^2 e^3 , substantially as and for the purpose described.

In witness whereof I have hereunto set my hand this 25th day of July, 1882.

JAMES TRIPP.
